CLAIM

The ornamental design for a light fixture for a canopy light system, as shown and described.

DESCRIPTION

FIG. 1 is a bottom perspective view of a light fixture for a canopy light system according to the present invention.

FIG. 2 is a top perspective view of the light fixture illustrated in FIG. 1.

FIG. 3 is a bottom plan view of the light fixture illustrated in FIG. 1.

FIG. 4 is a top plan view of the light fixture illustrated in FIG. 1.

FIG. 5 is a side elevation view of the light fixture illustrated in FIG. 1; and,

FIG. 6 is another side elevation view of the light fixture illustrated in FIG. 1.

The broken lines are directed to unclaimed elements of the design.
